The ornamental design of a cosmetic compact assembly, as shown and described.

DESCRIPTION

FIG. 1 is a right side and front perspective view of a cosmetic compact assembly showing my new design, with an upper door of the compact open and a lower door of the compact closed;

FIG. 2 is a right side and bottom perspective view thereof with the upper door of the compact closed and the bottom door of the compact open;

FIG. 3 is a right side elevational view of the compact shown separately for clarity and ease of illustration with both the upper door and the lower door open;

FIG. 4 is a rear elevational view of the compact with the upper door and the lower door open;

FIG. 5 is a bottom plan view of the compact with the upper door and the lower door closed, the top plan view being a mirror image of the bottom plan view;

FIG. 6 is a rear elevational view of the compact with the upper door and lower door closed;

FIG. 7 is a left side elevational view of the compact with the upper door and lower door closed;

FIG. 8 is a front elevational view of the compact with the upper door and the lower door closed; and,

FIG. 9 is a right side elevational view of the compact with the upper door and the lower door closed.

The undisclosed portions of the ring mounted components of the design are unornamented, and follow the configuration of the portions shown in FIGS. 1 and 2.
